PROGRAMMED AUTOMATIC COFFEE INFUSION MACHINE

Sanford E. Richeson, Brooklyn, N.Y., assignor to Alfred
B. Levine, Chevy Chase, Md.

Filed Sept. 3, 1965, Ser. No. 86,814

Term of patent 14 years

(Cl. D2—3)

FIG.1

FIG.2

FIG.5

FIG.3

FIG.4

FIG. 1 is a perspective view illustrating the front face, one side, and the top of a programmed automatic coffee infusion machine showing my new design.

FIG. 2 is a plan view observing the machine from the top.

FIG. 3 is a rear view of the machine.

FIG. 4 is a side view of the machine.

FIG. 5 is a side view of the other side of the machine.

I claim:

The ornamental design for a programmed automatic coffee infusion machine, as shown.
